UNITED STATES PATENT OFFICE.

CHARLES W. ANDREWS, OF DULUTH, MINNESOTA, AND WILLIAM B. CHAPMAN, OF BROOKLYN, NEW YORK, ASSIGNEES OF ONE-HALF TO CHAPMAN ENGINEERING COMPANY, A CORPORATION OF OHIO, AND ONE-HALF TO CHARLES W. ANDREWS.

GAS GENERATOR.

Application filed September 12, 1924. Serial No. 737,938.

The invention relates to a gas generator having special advantages for use in the production of water gas, although it should be understood that the same may be employed for other purposes, such as the production of producer gas from hard or soft fuel or the enrichment or cleaning of blast furnace and other gases.

In the production of water gas, the high temperatures and high pressures involved, as well as the fact that the steam run is both up and down, tend to the formation of large quantities of objectionable clinkers, which heretofore have been removed only by shutting down the generator periodically and taking out the clinkers manually with bars and sledge hammers. Both the delay and expense of the above operation are objectionable and the arduous labor involved therein has become a serious problem.

The primary object of the invention is to provide a gas generator which is mechanically operated in such manner as to avoid the necessity of the above manual operations under the difficult conditions that obtain in the production of water gas. In accordance with the present invention we provide an agitating member which sweeps around the lower portion of the ash bed in such a way as to thoroughly agitate the lower portion of the fire bed through the medium of the ash, prevent the formation of large clinkers and break up such as are formed, eliminate blow-holes and in general promote uniform conditions of combustion and gas generation within the generator.

The invention also aims to secure proper agitation as aforesaid without causing an unduly rapid ejection of the ash; that is to say, particularly in water gas installations, the proper agitation of the ash bed usually requires a speed of motion of the agitating member which would tend to push the ash too rapidly out of the ash bed, but according to the present invention the rate of removal of the ash is made independent of the speed of motion of the agitating member, thereby making it possible to move the latter as fast as may be desired. Although the ash agitating member preferably assists to some extent in the removal of the ash, the rate of ash removal is independently controlled.

We also prefer to provide in conjunction

with an ash agitating member of the above nature, a structure which will assist to break up clinkers of objectionable size and enable them to be mechanically removed along with the other ash.

Further objects and advantages of the invention will be in part obvious and in part specifically pointed out in the description hereinafter contained which, taken in conjunction with the accompanying drawings, discloses a preferred embodiment thereof; such embodiment, however, is to be considered merely as illustrative of its principles. In the drawings:

Fig. 1 is a vertical central section of the lower part of a gas producer constructed in accordance with the invention.

Figure 2 is a plan view of the structure shown in Fig. 1.

Fig. 3 is a section taken on the line 3—3 of Fig. 2, looking in the direction of the arrows.

Fig. 4 is a detail section taken on line 4—4 of Fig. 2.

Fig. 5 is a transverse section, and Fig. 6 is a central vertical section of a modified form of the invention.

Fig. 7 is a transverse section of a modified form of the invention, while Fig. 8 is a vertical section on line 8—8 of Fig. 7, looking in the direction of the arrows.

The invention is illustrated in Figs. 1 and 2 as applied to a gas generator having inner and outer side walls 1 and 2 which may be suitably water-cooled, and in the present instance the outer wall 2 is extended downwardly to the floor to act as a support for the side walls and provide within it an annular ash pit 3 which is located between the outer wall 2 above-mentioned and an inner annular partition 4, which in turn contains a chamber 5 therewithin. A grate, preferably of the type hereinafter described in greater detail, rests upon the wall 4 above described, and upon a fixed pedestal 6, whereby the chamber 5 serves as a pressure chamber for the air or steam which is fed into the same at certain stages by an inlet pipe 7 (Fig. 2), and receives gas at certain other stages which passes out through a gas outlet pipe 7.

In accordance with the present invention, we provide above the grate, an agitating member 8 which works in the ash supported

by the grate, such member, as shown in Figs. 1 and 2, being in the form of a beam of large enough cross section to project up into the ash bed to quite an extent, and thereby agitate the ash and firebed as thoroughly as desired, to remove blowholes, and in general produce uniform conditions in the firebed.

The above-mentioned motion of the ash-moving member is particularly desirable in 10 the operation of water gas generators where the high temperatures involved at certain stages, tend to produce clinkers of large size which have heretofore made it necessary to suspend the operation of the generator while they were being removed. With 15 a beam of the above character, it has been found that the formation of clinkers is minimized and the clinkers broken up to some extent by being crowded between the end 20 of the beam and the side wall of the producer, which preferably is provided with an annular wear plate 9 opposed to the outer ends of the beam.

The beam 8 is outstroking in its action, 25 continually crowding the ash toward the periphery of the grate, but its function of agitating the ash in an upward direction, producing an undulating or up and down motion, so as to produce uniform conditions in 30 the bottom of the firebed, is the primary one. Furthermore, from the standpoint of agitation of the firebed from underneath, it may be desirable to rotate the beam at a higher speed than that required to remove the ash 35 at the proper rate, and accordingly the generator preferably is so constructed as to cut down the amount of ash ejected from the ash bed by the beam to a point below the normal outstroking tendencies of the latter. 40 In the present instance the side wall 1 of the producer, as is shown more plainly in Fig. 1, is provided with an annular lip 1^a which extends down to approximately the level of the grate, thereby obstructing a direct outward path of travel of the ash, and an annular ash-discharge opening 10 underlies the outer end portions of the beam 8, such opening being of restricted size whereby only a limited amount of ash may drop there- 45 through as the beam rotates. The ash which is crowded outwardly by the beam, in excess of the amount which may drop downwardly through the ash discharge opening 10, is permitted to relieve itself by moving upwardly adjacent the side walls 1, which does 50 not confine the ash against such upward relief. The result is that the beam may be speeded up as much as desired to properly agitate the firebed from underneath, without 55 ejecting the ash too rapidly.

The movement imparted to the fuel bed by the rotating beam is primarily an up and down or undulating one, although there is also to a lesser extent a twisting movement 60 and an outward movement, all caused by the

rotation of the beam. It has been found that the agitation of the fuel bed from above does not cause motion therein more than a foot or two below the actual reach of the agitating member. The various types of agitation employed in the ashes heretofore have been primarily horizontal in their effect upon the ash bed and primarily employed for ejecting ash from the ash bed.

The motion produced by the type of agitator employed herein extends nearly to the top surface of the fuel and should the fuel be dumped all in the center of the fuel bed, for example, the action of the beam will spread the fuel out satisfactorily over the 75 entire surface of the fuel bed. Thus agitation of this nature renders unnecessary the usual spreading out and agitation of the fuel from above.

In the present embodiment of the invention, the beam 8 is rotated by means of a drive ring 11 which surrounds the pressure chamber 5 and is connected to the beam near the outer extremities of the latter. As shown, the drive ring 11 rides upon ball 75 bearings 12, which are supported by an annular shelf 13 detachably mounted upon partition 4. The drive ring 11 is rotated in any suitable manner, as by providing gear teeth 14 thereon which mesh with a pinion 15, which latter is carried by drive shaft 16 connected to a suitable variable speed driving mechanism of suitable character, which need not be described in detail herein. Preferably the drive shaft 16 and associated parts are 90 located within the confines of the producer side wall 2, as by dividing off a portion of the chamber 3, by means of partitions 17 and 18 (Fig. 2) to form a housing for the driving parts.

The rotary motion of the drive ring 11 serves to carry around with the ring that portion of the ash lying in its vicinity, whereby the clinkers in the ash are ground up between themselves and also by being 100 crushed against the plate 9 previously mentioned. If desired, the ring 11 may be provided with projections or corrugations similar to those later described herein in connection with Fig. 5, for the purpose of 105 promoting the rotation of the ash and breaking of the clinkers.

The illustrated form of generator is of the dry bottom type, and the ash beam 8 is made hollow, to receive cooling water led thereto, as by means of a rotatable water pipe 19 located within the pedestal 6, at the axis of rotation of the beam. It is preferred also to water-cool the drive ring 11 by providing water connections 20 at the outer portions of the beam 8, leading from its interior to the hollow interior of drive ring 11, thus circulating water through the latter after it has passed through beam 8. The water may 115 pass out into the above chamber through a 120

suitable number of openings 21 in drive ring 11.

In order further to assist in controlling the amount of ash ejected through the opening 10 above-mentioned by the beam, it is preferred to provide an annular ash-receptacle 22 beneath said opening which receives the ash falling therethrough, and thus prevents further ash from being ejected so long as the trough 22 remains full. In the present instance the receptacle 22 is mounted upon the drive ring 11 and rotates therewith, and an adjustable device is provided for removing ash from the trough at the desired rate, thus permitting any desired rate of ash removal to be maintained with different rates of agitation. As shown, an ash plow 23 projects down into the receptacle 22, and is made adjustable in position, as by mounting the same upon a spindle 24, which is provided with an exterior operating handle 25 having a pin 26 which may fit into any one of a series of holes 27 in a sector plate 28. Thus the ash plow 23 projects down into the receptacle 22 a distance depending upon the setting of handle 25, and as the receptacle rotates, the ash is removed therefrom at a corresponding rate, and further ash is permitted to drop through opening 10 into receptacle 22, at a corresponding rate. Ash plows 23, of which any desired number may be employed, may be disposed at various points above the chamber 3 so as to deflect the ash to drop into said chamber in front of a corresponding number of ash doors 29 (Fig. 2) located beneath the ash plows. In the present embodiment of the invention, the ash pit is located within the gas-tight housing of the producer, and thus when the above doors 29 are opened, the pressure within the generator may serve to assist in ejecting ash if desired.

The grate is preferably made in the form of sectorlike sections 30 which are supported centrally by the pedestal 6, and at the outer ends by the partition wall 4. The draft openings 31 (Fig. 3) of the grate are also preferably located beneath the inclined ledges 32 in the sections 30, whereby the motion of the ash-agitating member tends to sweep the ash up the ledges away from the draft openings, instead of crowding the ash into the latter.

Fig. 4 shows the ash-agitating beam of Figs. 1 and 2 as having a substantially triangular cross section, with its inclined side face forwardly directed to gradually undulate the ash as the beam moves around.

The beam also is preferably provided with forwardly directed teeth 33 which plow into the ash and check to some extent the out-stroking action of the beam.

In connection with an ash-agitating member of the above nature, it is advantageous in many instances to employ a device for

crushing clinkers to facilitate their removal from the ash bed. In Figs. 5 and 6 we have illustrated a gas generator which is generally similar to the one previously described in connection with Figs. 1 and 2, in that its inner side wall 1^a extends down below the lower working level of an ash-agitating member 8^a, the latter being supported and moved by a drive ring 11^a, which supports an intermediate ash receptacle 22^a. This embodiment of the invention, however, is provided with an ash-crushing device interposed between agitating member 8^a and the ash-discharge opening 10^a, which ash-crushing device, consisting of an annular member 34 supported by drive ring 11^a grinds the clinkers against a wear plate 9^a. Preferably the opposed ash-crushing faces of members 34 and 9^a converge downwardly, as indicated in Fig. 6, whereby the clinkers are crushed progressively to smaller size as they pass toward the ash-discharge opening 10^a. Fig. 5 also shows the member 34 as having oblique corrugations providing inclined ridges 35 thereon adapted to urge the clinkers downwardly and into contact with the corrugated faces of wear plate 9^a.

Thus the above crushing device serves to break up any clinkers which otherwise could not be mechanically removed from the generator.

In Figs. 7 and 8 we have also illustrated another embodiment of the invention having an ash-agitating member which functions similarly to the one previously described, but which is of different construction. This latter type of agitating member is in the form of a shell supported upon a drive ring 11^b carrying an intermediate ash receptacle 22^b, both of general construction similar to the members 11^a and 22^a above described, the ring 11^b being water-cooled by a diametrically disposed pipe 36 connected at the centre of rotation of the beam with a water pipe 19^b similar to pipe 19 above described.

The top surface of the agitating shell is made up of a series of inclined walls 37 which support the ash bed, and the rearward higher edge 37^a of each wall 37, overlaps to some extent the forward lower edge 37^b of the wall 37 next behind.

A vertical ledge 38 also depends from each of the rearward high edges of the walls 37 and overhangs an upstanding ledge 39 on each of the forward edges 37^b, thus providing a series of draft openings 40 communicating with the interior of the shell, whereby the latter acts as a grate as well as an agitator. As the shell rotates, the inclined walls 37 gradually elevate the ash until the high points 37^a of such walls are reached, when the ash drops abruptly, thus producing an undulating movement of the ash bed analogous to that obtained by the use of the beam 8 previously described.

The annular side walls 41 of the shell may also function as an ash crusher, forcing the clinkers against a wear plate 9^b, similar to members 9 and 9^a previously described. As shown, the shell above-mentioned is positioned somewhat eccentrically upon the drive ring 11^b whereby the side walls 41 are outstroking in their action, similar to the beam 8.

10 The inner side wall 1^b also is extended down to the lower working limits of the shell to prevent the free outward movement of the ash, whereby the latter passes through the discharge opening 10^b into the receptacle 22^b, at a rate conforming to that at which the ash is removed from the receptacle.

While certain preferred embodiments of the invention have been described, it will be obvious that many changes may be made 20 therein without departing from its principles as defined in the appended claims.

We claim:

1. A gas generator adapted to have fuel and ash beds and having a rotary ash and fuel 25 agitating member adapted to operate in the ash bed, a drive ring connected to an outer part of said member, cooling water connections leading to the axis of rotation of said member, and cooling water connections 30 for said ring leading thereto from said outer part of said member.

2. A gas generator having a grate adapted to support an ash bed, a pressure equalizing chamber underlying substantially all of 35 said grate, an up and outstroking ash and fuel agitating member adapted to operate in said ash bed, the side walls of the generator extending down substantially to the lower working limit of said member, an annular ash pit surrounding the pressure chamber above-mentioned, and an annular intermediate ash receptacle communicating 40 between said ash bed and the ash pit.

3. A gas generator having a grate adapted to support an ash bed, a pressure equalizing chamber underlying substantially all of 45 said grate, an up and outstroking ash and fuel agitating member adapted to operate in said ash bed, the side walls of the generator 50 extending down substantially to the lower working limit of the ash bed, an annular ash pit surrounding the pressure chamber above-mentioned, and an annular intermediate ash receptacle moving with said ash- 55 agitating member and communicating between said ash bed and the ash pit.

4. A gas generator having an ash bed, a pressure equalizing chamber located beneath the same, inlet and outlet connections for 60 gases leading to said chamber, a stationary grate supporting the ash bed, a rotary ash-agitating member adapted to operate in said ash bed immediately over the grate, and a cooling water connection leading upwardly 65 through said chamber and grate to the centre

of rotation of said member, and an annular ash receptacle surrounding said grate.

5. In a gas generator having a grate adapted to support an ash bed, a pressure equalizing chamber underlying substantially all of 70 said grate, inlet and outlet connections for gases leading to said chamber, and an ash pit surrounding said pressure chamber.

6. A gas generator having an annular wall adapted to enclose a fuel and ash bed, a 75 stationary grate underlying and supporting the fuel and ash bed, a rotary dry annular ash-receiving trough underlying said wall, a rotary out and upstroking agitator operating immediately over the grate, an annular 80 lip extending down from said wall and projecting down into said trough to dam the outward flow of ash through the trough, the portion of the trough which is outside of said lip being surrounded by a gas-tight housing 85 of the generator.

7. A gas generator adapted to have fuel and ash beds and having stationary side walls and a stationary grate extending substantially from wall to wall of the generator 90 so as to support substantially all of the ash bed, a pressure equalizing chamber underlying substantially all of the grate, a rotary out and upstroking agitator operating immediately over the grate and sweeping 95 through the bottom of the ash bed, and means adjustable to different rates of ash removal with a given rate of operation of the agitator, for controlling the rate of ash removal from the ash bed.

8. A gas generator adapted to have fuel and ash beds and comprising stationary side walls and an up and outstroking ash moving and fuel agitating member adapted to sweep through the ash bed, a grate adapted to support substantially all of the ash bed, said generator having an ash discharge opening located near the outer portion of said member and outside of the periphery of said grate, a drive ring for said member connected to the outer portion thereof, and an ash receptacle connected to said ring and adapted to receive ash passing through said opening.

9. A gas generator adapted to have fuel 115 and ash beds and comprising stationary side walls and an up and outstroking ash moving and fuel agitating member adapted to sweep through the ash bed, a grate adapted to support substantially all of the ash bed, 120 said generator having an ash discharge opening located near the outer portion of said member and outside of the periphery of said grate, a drive ring for said member connected to the outer portion thereof, an 125 ash receptacle connected to said ring and adapted to receive ash passing through said opening, and a member adjustable to remove ash from said receptacle at different rates.

100

10. A gas generator adapted to have fuel and ash beds and having a gas-tight housing, a grate underlying substantially all of the ash bed, a pressure equalizing chamber underlying substantially all of the grate, an up and outstroking ash moving and fuel agitating member adapted to work in said ash bed, an ash pit surrounding said pressure equalizing chamber and located within the 10 gas-tight housing of the generator, and an intermediate ash receptacle disposed near the outer portion of said member and communicating with said ash pit, said receptacle receiving the ash by gravity from the ash bed.
11. A gas generator adapted to have fuel and ash beds, a grate underlying substantially all of the ash bed, a pressure equalizing chamber underlying substantially all of said grate, an up and outstroking ash-moving member adapted to work in said ash bed, a drive ring for said member surrounding said pressure chamber, bearing means for said drive ring mounted upon the walls 20 of said chamber, an ash-pit surrounding said pressure chamber, and an intermediate ash receptacle interposed between the outer portion of the member and said ash-pit.
12. A gas generator adapted to have fuel and ash beds, a stationary grate underlying substantially all of the ash bed, a pressure equalizing chamber underlying substantially all of the grate, inlet and outlet connections for gases leading to said chamber, and an ash pit surrounding said pressure chamber.
13. A gas generator adapted to have fuel and ash beds and having a stationary grate extending substantially from wall to wall of
- the generator so as to support substantially all of the ash bed, a pressure equalizing chamber underlying substantially all of the grate, an out and upstroking agitator operating immediately over the grate, and means adjustable to maintain a different rate of ash removal with different rates of operation of the agitator, for controlling the rate of ash removal from the ash bed, said generator being provided with a gas-tight housing which surrounds said chamber and ash-removing means, to provide a seal for the interior of the generator.
14. A gas generator adapted to have fuel and ash beds, and having a stationary grate adapted to support substantially all of the fuel and ash beds, said generator also having a stationary interior side wall enclosing said fuel and ash beds, said grate being spaced from said wall to some extent to provide an ash discharge opening between the periphery of the grate and said side wall, a rotary up and out stroking agitating member operating immediately over the grate and overhanging said ash discharge opening, said agitating member having its outer end extending out nearly to said side wall so as to be capable of breaking up clinker between the outer portion of the agitating member and the surrounding side wall, as well as lifting and passing under clinker which is not so broken up, and means being provided to afford water cooling connections to the interior of said agitating member.

In witness whereof, we have hereunto set our hands this 3d day of September, 1924.
